UNITED STATES PATENT OFFICE.

CHARLES E. HEYER, OF CHICAGO, ILLINOIS, ASSIGNOR TO ARTHUR M. BARNHART AND ALSON E. BARNHART, BOTH OF SAME PLACE.

DESIGN FOR A FONT OF PRINTING-TYPE.

SPECIFICATION forming part of Design No. 14,503, dated December 25, 1883.

Application filed October 26, 1883. Term of patent 14 years.

To all whom it may concern:

Be it known that I, CHARLES E. HEYER, a citizen of the United States, residing in the city of Chicago, county of Cook, and State of Illinois, have invented and produced a new and original Design for a Font of Printing-Types, of which the following is a specification, reference being had to the accompanying illustration, forming a part hereof.

10 The letter has the appearance of being embossed or raised, the white tint being filled with horizontal hair-lines running parallel. Each of the capital letters, figures, points, character "&," and dollar-mark has a heavy 15 shade-line with a hair-line on the right side, while a hair-line only is shown on the left side. Each character of my design has a horizontal shading, excepting where spurs enter the top and bottom of said character. Some have four 20 of these spurs, as shown in capitals B C D E G H K M N O R S T U X Z, figures 3 6 9 0; others have three, as shown in capitals A F J L P V Y, and no character, excepting the end 25 ornament, period, comma, semicolon, colon, hyphen, and apostrophe has less than one.

Capital A has a spur entering the top extending downward, and is connected with the ceriph, which ceriph is joined to the hair-line on the left side of the letter. Two spurs enter the bottom and extend upward, and are connected with the horizontal ceriph at the bottom of the letter. The cross-stroke is near the bottom of the letter. The hair-line on the left side of capitals B D E F K P R and the heavy and hair line on right side and hair-line on left side of 30 capitals H I J L M N U and figure 1 are perpendicular until near the top and bottom of the characters, at which point they curve. The flags of letters C E F G J L S T Z and dollar-mark and figures 2 3 5 6 9 and interrogation 35 point have an inward-bending appearance.

I claim—

The design for a font of printing-types, consisting of capital letters, figures, points, and an ornamental end piece or scroll, as described, 40 and shown in the accompanying illustration.

CHARLES E. HEYER.
